UNITED STATES PATENT OFFICE.

ELBERT VINTON MENDENHALL, OF LOS ANGELES, CALIFORNIA.

STANDING NOTE-BOOK.

SPECIFICATION forming part of Letters Patent No. 681,832, dated September 3, 1901.

Application filed June 14, 1900. Serial No. 20,351. (No model.)

To all whom it may concern:

Be it known that I, ELBERT VINTON MENDENHALL, a citizen of the United States, residing at Los Angeles, in the county of Los Angeles and State of California, have invented a new and useful Improvement in Standing Note-Books, of which the following is a specification.

This invention is more particularly adapted for note-books for stenographers' and reporters' use, but may be applied to any book which it is desired to use open in standing position, supporting means being supplied either by stiff covers pertaining to the book or by stiff members which will serve the purpose.

The object of the invention is to provide a simple and inexpensive appliance by means of which the covers of the note-book can be rigidly held in a desirable position to form an easel-support for the note-book, thus to enable the user to conveniently station the book in a substantially upright position for inspection while transcribing the notes, &c.

It is an object of my invention to provide for practically rigid connection of the two covers at a desired angle.

In carrying out my invention I may use stiffened covers, to which the ordinary note-books of commerce may be detachably applied, so that the person desiring to use the ordinary note-books now manufactured may do so by supplying himself with the independent cover provided with my invention. The use of supplemental covers for holding note-books is well understood in the art, and for that reason I have not deemed an illustration of such an appliance necessary in this application, but have shown the invention applied to a note-book having stiff covers permanently attached in the ordinary way. I have also shown leaf-springs, which are preferred, although it is to be understood that round or square wire may be used for the springs instead of the flat thin wire shown.

The accompanying drawings illustrate my invention.

Figure I is a perspective view of my invention as it appears in use. A portion of the book is broken away for clearness of illustration. Fig. II is a longitudinal mid-section of

the note-book, showing open position and one form of the support. Fig. III is a view showing one form of spring-tie and one of the modes of fastening the same to the book-cover. Fig. IV is an edge elevation of the spring-tie detached. Fig. V shows a preferred form of clasp before bending for fastening the spring-tie to the cover. Fig. VI shows a preferred form of spring to be used with the clasp shown in Fig. V. Fig. VII shows said preferred forms of clasp and spring attached to the cover, a fragment of which is shown. Fig. VIII is a longitudinal section on line VIII VIII, Fig. VII. Fig. IX is a section on line IX IX, Fig. VII.

The drawings show a note-book furnished with stiff covers 1 2 and a flexible back 3, to which the leaves 4 are fastened in the usual way. A socket or catch-seat may be provided in any suitable manner on the back of one of the covers to seat one end of a tie fastened to the other cover.

5 indicates a recess or socket for this purpose on one cover at a distance from the flexible back 3 to cause the tie when seated to hold the covers apart at a desired angle when the book is opened.

6 indicates a spring-tie fastened at one end to the opposite cover and furnished with a catch or hook 7 at the free end of the spring. Said spring is fastened to said opposite cover at a suitable distance from the flexible back 3, so that when sprung away from its cover and caught in the seat of the other cover it will form a tie between the two covers to hold the covers practically rigid at a desirable angle, thus enabling the book to stand firmly alone when the catch or hook 7 of the spring of one cover is caught in the socket of the opposite cover. The book-back 3 is bendable, and the leaves 4 are fastened thereto in the ordinary manner to be thrown over from one cover to the other cover in the usual manner, as indicated in the drawings.

It is desirable in practical use that each of the stiff covers shall be permanently provided with a tie and with a socket, so that the tie may be extended from the one cover to the other, and vice versa, indiscriminately. For this purpose the spring 6 is shown as a

leaf-spring made of a thin strip of steel or other suitable material provided at or near one end with an opening to form the seat or socket 5 and bent at the free end to form the 5 catch or hook 7. The leaf-springs are fastened to the backs, respectively, by any suitable means. Figs. II and III show a staple 8, embracing the bar 9, formed between the opening 5 and the margin of the spring 6 and 10 inserted through the stiff cover 1 or 2, as the case may be, and clenched, and a staple 10, embracing the body of the spring 6 between the opening 5 and the free end and inserted through the cover and clenched. The ties 15 can thus be made and applied to the covers at a small expense. The staple 10 is applied to the spring at a considerable distance from the free end, which is provided with a catch or hook 7, so as to allow a considerable spring 20 arm or body between the fastening and the free end to form the tie between the two covers when the book is in the easel position. (Shown in Figs. I and II.) Preferably the tie for each cover is so located that when in the 25 closed position the catch or hook 7 will come to the margin of the cover where the flexible back 3 joins the same, so that the catch fits over the edge of the cover at the line where the flexible back 3 is attached to the same, 30 thus allowing the spring to lie close against the cover. The spring is reduced in width at the free end to form a catch narrow enough to be inserted into the seat or socket 5 provided therefor on the opposite cover.

35 In practice when it is desired to stand the book in upright position for transcribing notes the body of one of the springs 6 will be bent away from the cover to which it is attached and bent out to extend at an angle 40 with such cover, and the book will be opened to bring the two covers into position relative to each other to allow the catch or hook 7 of the spring on the one cover to be caught in the socket or seat therefor on the other cover.

45 When thus adjusted, the book is rigidly held in position to be stood upright, as shown in Figs. I and II. In Fig. I, I have shown a marker 12 to serve as a guide for the eye of the copyist.

50 Referring to Figs. V, VI, VII, and VIII, 6' indicates a preferred form of leaf-spring to be stamped from sheet metal without waste. The spring 6' is formed with complementary ends, one having a recess 6" and the other a 55 tongue 6'", which corresponds in outline to the recess 6". The end of the tongue 6'" is bent to form a hook 7', which corresponds to the hook 7. (Shown in Figs. II, III, and IV.) In Fig. V, I have shown a staple 8' cut from 60 a single piece of sheet metal and serving the purpose of the two staples 8 and 10. (Shown in Figs. I, II, and III.) 8" indicates the clenching arms or limbs of the staple, which limbs are formed integral with the clasp 8' 65 and are bent from one side of the plate to pass through the stiff member of the book.

cover, as clearly shown in Fig. VIII. The clasp-wings 8"" are to be bent along the dotted lines a, so as to fold over the spring 6', as clearly shown in Fig. IX. In practical manufacture the wings 8"" will be bent with considerable pressure upon the recessed end of the spring 6', so that the spring will be securely held in the clasp. Then to apply the same to the book-cover the staple-limbs 8" 75 will be inserted from the outside through the cover and will be clenched on the inside of the cover, as indicated in Fig. VIII. The wings 8"" extend across the recess 6" of the spring 6', thus forming on the back of the 80 cover of the book a socket or seat 5 to receive the hook 7 or 7'.

It is to be understood that, if preferred, only one instead of both of the book-covers 85 may be furnished with a spring and the other cover may be furnished in any desired way with a socket for the hook 7 or 7'.

Various changes in form, proportion, fastenings, and other details may be resorted to without departing from the spirit of this 90 invention, and I do not limit myself to the specific constructions of spring-ties, sockets, and fastenings shown in the drawings.

What I claim, and desire to secure by Letters Patent of the United States, is— 95

1. A note-book comprising stiff covers and bendable back; one of said covers being furnished with a catch-seat; and a spring fastened to the back of the other cover and furnished with a catch to catch in said seat. 100

2. A note-book furnished with stiff covers and bendable back; leaf-springs fastened to the covers respectively and each furnished at the free end with a catch and at the fastened end with a seat for the catch of the 105 other spring.

3. A book comprising a stiff cover; a leaf-spring furnished at one end with a catch and at the other end with an opening corresponding to the catch; a staple embracing the 110 spring at the end furnished with said opening, and having its limbs inserted through the book-cover and clenched, whereby a catch socket or seat is provided at the end of the spring opposite the catch substantially as 115 and for the purpose set forth.

4. The combination with two stiff covers and flexible back, of an attachment consisting of a spring, fastened at one end to one cover, the other end of the spring being free 120 and furnished with a hook or catch; and a seat on the other cover to seat the catch or hook, substantially as specified.

5. The combination of two stiff covers, flexible back and attachments thereto, composed of springs fastened to the covers, respectively, and provided at loose end with catch or hook and seats on the covers respectively for receiving the catches or hooks substantially as specified. 125

6. The combination of two stiff covers and flexible back, and attachments thereto com- 130

posed of springs, respectively, provided at loose end with a catch or hook and fastened at the other end, and suitable staples or clasps respectively providing a receptacle for catch or hook on loose end of the other spring, substantially as specified.

5 In testimony whereof I have signed my

name to this specification, in the presence of two subscribing witnesses, at Los Angeles, California, this 25th day of May, 1900.

ELBERT VINTON MENDENHALL.
